UNITED STATES PATENT OFFICE.

ALEXANDER McKNIGHT, OF BROOKLYN, NEW YORK.

BED-FRAME.

1,144,661.

Specification of Letters Patent. Patented June 29, 1915.

Application filed February 10, 1913. Serial No. 747,411.

To all whom it may concern:

Be it known that I, ALEXANDER McKNIGHT, a citizen of the United States, residing at Brooklyn, in the county of Kings 5 and State of New York, have invented a new and useful Improvement in Bed-Frames, of which the following is a specification.

My invention relates particularly to bed frames in which the side rails and legs or corner standards are rigidly united by suitable corner pieces, and the side frames thus produced are connected by end members swiveled to the sides which securely hold 15 the bed frame in normal position, but permit it to be collapsed or folded by a horizontal angular movement of the end members relative to the side rails.

An object of the invention is to provide 20 a simple and inexpensive structure of this character in which the bed frame is rigidly held in normal position but which may be easily and quickly folded.

Another object of the invention is to provide 25 a corner bracket or connecting member which will permanently hold the legs or standards rigid with the side rails, and which will combine cheapness of construction, simplicity, strength, durability, and a minimum weight.

The bed frame may be easily and quickly folded to economize space, permit sweeping of the floor, etc., and can also be readily taken apart and set up again.

Other objects of the invention and the exact nature thereof will appear herein-after.

In the accompanying drawings which illustrate the principles of my invention, 40 Figure 1 is a perspective view of a bed frame. Fig. 2 is an enlarged sectional elevation showing the connecting means at a corner of the bed frame. Fig. 3 is a similar view of an alternative construction. Fig. 4 is an elevation view of one of the ends of 45 the bed frame. Figs. 5 and 6 are detail views in end and side elevation respectively, illustrating an alternative form of side rail. Fig. 7 is a view of a coupling which may 50 be used to support the side frames, when the ends are removed. Fig. 8 is a plan view showing the side frames so supported. Fig. 9 is a plan view of the bed frame folded, and also showing in dotted lines the frame 55 partly folded.

The bed frame comprises side rails 1, legs

2, corner brackets or couplings 3, and end frames 4, 5. The couplings 3 are in the form of T couplings having their lower ends internally screw-threaded to receive the 60 threaded upper ends of the legs or standards 2. The lateral extensions 6 of the couplings are likewise threaded to receive the threaded ends of the side rails 1. A strong and rigid permanent connection is 65 thus formed between the side rails and the legs of the bed, which together may be considered as constituting the side frames. These side frames are connected by end frames 4 and 5, each of which comprises 70 vertical end members 7 adapted to extend through the couplings 3 and telescope with the legs 2. The end members 7 may consist of tubular coupling pins or tenons rigidly secured in the frames 4 by rivet 75 bolts 8 or in any other suitable manner. The lower ends 9 of the members 7 are preferably beveled or tapered to assist in guiding the end frames when they are being connected to the side frames. The members 80 7 have a free telescopic connection with the legs so that the end frames can be readily lifted and removed from the side frames, but they are a sufficiently close fit to firmly hold the bed frame rigid. The downward 85 movement of the end frames 4 and 5 is limited by pins 10 secured in the members 7 and adapted to seat in recesses 11 formed in the upper edges of the couplings 3. The pins 10 entering the notches 11 serve the 90 double purpose of limiting the downward movement of the end frames and holding them against angular movement relatively to the side frames in a horizontal direction.

The bed frame is adapted to be folded or 95 collapsed by an angular or twisting movement of the end frames relatively to the side frames in a horizontal direction. Thus, a person standing at one end of the bed can by turning the end frame fold the bed 100 to the position shown in Fig. 9. The end frames will be cammed upward by the holding pins riding up the inclined sides of the notches 11 at the beginning of the folding movement, after which the frame will move 105 freely to the folded position. If preferred, the holding pins 10 may be supplied at only one end of the bed, so that by lifting said end upward a short distance the holding pins will be freed and offer no resistance 110 to the folding movement of the frame. If desired notches 11' as shown in Fig. 3 can

be used instead of the notches 11. The notches 11' are formed with perpendicular sides to form a positive lock. The pins 10 may be round as shown, or shaped to conform to the notches 11 or 11'.

- 5 The ends 4 and 5 may be made of metal tubing of the same diameter as the legs 2, as shown in Figs. 1 and 2, or said ends may be made of smaller tubing that will telescope 10 with the legs as indicated in Fig. 3, thereby dispensing with the additional connecting pieces 7. As indicated in Fig. 4, one vertical arm of each end frame is preferably somewhat longer than the other to assist in assembling the bed frame. The longer arm is inserted first and supports one side frame and permits the other arm to be readily guided and inserted in its socket. The end frame 5 at the foot of the bed as shown in 15 Fig. 1, rises only a short distance above the couplings 3 which is a valuable feature for an invalid's bed, and the like. A higher frame like the head frame 4 can of course be used at the foot of the bed if preferred. 20 25 If desired the side rails may be made of angle irons 21 (Figs. 5 and 6) to which tubular end pieces 22 are rigidly secured by rivet bolts 23. The end pieces 22 may correspond to the ends of the rails 1.
- 30 When the bed is located in a small room or where there is insufficient room to accommodate the increased length of the frame when folded, I employ a holder 15 to support the side frames in the position shown 35 in Fig. 8. This device permits the bed frame to be quickly folded or adjusted to a position where it will take up but little space. To apply the holder 15, one end frame, as 5, is removed, the adjacent ends of 40 the side rails brought nearly together, and the ends of the holder 15 dropped down into the sockets 3. The head frame 4 can then be removed and the adjacent ends of the side frames swung toward each other to the position 45 shown in Fig. 8. The holder 15 holds the side frames securely in an upright position.

Ornamental collars 24 may be placed on the end frames in position to rest on the 50 couplings 3 if desired.

I wish not to be limited to the particular features of construction herein disclosed as various modifications might be made by those skilled in the art without departing 55 from the spirit and scope of my invention.

What I claim as new and desire to secure by Letters Patent of the United States is:—

- 60 1. A collapsible bed frame comprising the combination of side rails, legs rigidly secured thereto, and end members extending between and having a swivel connection with said legs permitting a relative pivotal movement of the sides and ends of the frame to move the sides toward each other and 65 swing the ends toward positions in line with

the sides, said end members being bodily removable to entirely disconnect the side rails from each other and from the end members.

2. A collapsible bed frame, comprising the combination of sides, uprights secured thereto and formed with vertical sockets, connecting members forming the ends of the frame, said members each having depending ends extending into said sockets and rotatable therein while the ends are both connected 75 to each of the sides to permit the sides to be brought together and the ends to swing toward a position of alinement with the sides.

3. In a folding bed frame, the combination of sides, corner uprights secured thereto 80 and formed with vertical sockets, and end members each having depending ends entering the sockets and uniting the sides and end members to form a rectangular frame, the said depending ends being rotatable in the 85 sockets while the sides and end members are thus united to permit the frame to be folded, said depending ends and sockets comprising means to hold the frame in normal open position, said holding means being releasable 90 to permit the frame to be folded.

4. In a folding bed frame, the combination of the sides, uprights at the corners of the frame formed with vertical sockets, and end members having depending ends 95 entering the sockets and permitting relative pivotal movement of the sides and end members while said sides and end members are united to form a frame, thereby permitting the frame to be folded, said ends 100 and sockets comprising means to hold the end members perpendicular to the sides, said holding means being releasable by an upward movement of an end member without disconnecting it from its sockets.

5. In a folding bed frame, the combination of sides, uprights at the ends of the said sides, said uprights formed with vertical sockets, end members having depending ends entering the sockets to connect the sides and end members, and permitting relative pivotal movement of the sides and end members while thus connected, to thereby fold the frame, and means to hold the end members perpendicular to the sides, said holding 115 comprising cams formed to permit said members to be released by pressure in a direction to produce said pivotal movement.

6. In a bed frame, the combination of side rails, uprights, means rigidly connecting the uprights to the side rails, said uprights having their upper ends hollow to form sockets, end members having depending ends entering the sockets and thereby pivotally connecting the end members to said uprights, and pins carried by said members and entering notches in the uprights to hold the parts against said pivotal movement.

7. In a bed frame, the combination of side rails, legs, corner brackets each comprising 130

- an upright tubular portion rigidly connected with a leg and an integral horizontal portion rigidly connected with the end of a side rail so that each side rail with its connected brackets and legs forms an independent unit, and end members having depending ends extending through said upright tubular portions of the brackets and nesting within the legs and thereby connecting the 5 sides to form a frame, the end members being removable from said units and the latter thereby disconnected from each other.
8. In a bed frame, the combination of side rails, legs, corner brackets or couplings each 10 comprising a horizontal screw-threaded socket with which the end of a side rail has a screw-threaded connection and a vertical tubular portion integral with said socket, and frame ends having depending portions 15 freely entering said tubular portions of the couplings, so that the ends may be lifted bodily from the couplings and leave the side rails entirely disconnected from each other.
9. A folding bed frame comprising the 20 combination of sides and ends connected by 25

vertical pivots, said sides and ends relatively movable about said pivots to fold the frame, and horizontal locking pins, engaging notches formed in the frame, said notches and pins locking the bed frame in 30 open or non-folded position, said pins releasable from the notches by an upward movement of the ends relative to sides to permit the frame to be folded.

10. In a bed, the combination of sides 35 comprising side rails and legs rigidly secured thereto, and ends having vertical members swiveled in said legs and connecting the sides and holding them upright, the ends being vertically removable to disconnect the sides, one of said members of each end being longer than the other to facilitate the assembling of the bed.

In testimony whereof I have signed my name to this specification in the presence of 45 two subscribing witnesses.

ALEXANDER McKNIGHT.
